US00D965787S

(12) **United States Design Patent** (10) Patent No.: **US D965,787 S**
(45) Date of Patent: **** Oct. 4, 2022**

(54) **STENT**

(71) Applicants: **THE ASAN FOUNDATION**, Seoul (KR); **University of Ulsan Foundation For Industry Cooperation**, Ulsan (KR); **INSUNG MEDICAL CO., LTD.**, Wonju-si (KR)

(72) Inventors: **Do Hyun Park**, Seoul (KR); **Ban Joon Park**, Wonju-si (KR)

(73) Assignees: **THE ASAN FOUNDATION**, Seoul (KR); **University of Ulsan Foundation for Industry Cooperation**, Ulsan (KR); **INSUNG MEDICAL CO., LTD.**, Wonju-si (KR)

(**) Term: **15 Years**

(21) Appl. No.: **35/512,011**

(22) Filed: **Dec. 11, 2020**

(80) **Hague Agreement Data**

Int. Filing Date: **Dec. 11, 2020**

Int. Reg. No.: **DM/212470**

Int. Reg. Date: **Dec. 11, 2020**

Int. Reg. Pub. Date: **Jun. 11, 2021**

(30) **Foreign Application Priority Data**

Jun. 15, 2020 (KR) 30-2020-0026897
(51) LOC (13) Cl. **24-03**
(52) U.S. Cl. USPC **D24/155**
(58) **Field of Classification Search** USPC D24/107, 133, 135, 141, 144–146, 151, D24/152, 154–156
CPC A61F 2/82; A61F 2/885; A61F 2/90; A61F 2/954
